UNITED STATES PATENT OFFICE.

WILLIAM JOSEPH MORAN, OF YONKERS, NEW YORK.

PROTECTIVE UNIFORM.

1,090,742.

Specification of Letters Patent. Patented Mar. 17, 1914.

Application filed October 7, 1907. Serial No. 396,305.

To all whom it may concern:

Be it known that I, WILLIAM JOSEPH MORAN, a citizen of the United States, residing at Yonkers, in the county of West Chester and State of New York, have invented new and useful Improvements in Protective Uniforms, of which the following is a specification.

The invention relates generally to an improvement in fire and gas proof suits, and particularly to a protective uniform in the use of which the wearer will be effectively guarded against injury in those situations otherwise dangerous on account of fire, deleterious gases, or the like.

The main object of the present invention is the provision of a mask designed primarily for the protection of the head of the wearer and constructed to permit its ready application and removal.

A further object of the invention is the provision of a fire mask integrally provided with an air chamber in which air may be stored under pressure and supplied to the wearer under his direct manual control, the construction including an auxiliary air chamber or tank in communication with the main chamber, which auxiliary chamber is arranged to replenish the charge in the main chamber upon undue exhaustion of the latter charge, or may be utilized to furnish the air supply for an independent mask forming part of the suit and intended for the use of another being rescued or removed from the dangerous influences.

Another object of the present invention is the utilization of an independent reservoir adapted to be carried by the wearer or removably connected to the suit and having independent communication with the mask, said reservoir being adapted for use in the event of extended service of the apparatus, or for disconnection from the mask and suit and utilization as an auxiliary supply chamber for a mask carried with the reservoir and adapted to protect a victim against the surrounding dangerous influences in the event such victim cannot be promptly removed, as through the finding of two or more persons by the rescuer and the impossibility of removing more than one at a time.

Another object of the invention is the production of a mask in the use of which the ordinary functions of the wearer will suffer the minimum impairment, practically full normal sight and hearing being permitted,

the respiratory function being full and unimpeded, and a simple means of communication being provided whereby the wearer without danger to himself may communicate with another who may or may not be provided with the improved apparatus.

Another object of the invention is the provision of lighting means by which the wearer of the mask may direct at will a more or less intense light in advance, the construction including the disposition of the light either above or below the sight ports of the mask, whereby said light may be effectively directed in accordance with the particular existing condition.

With the above objects in view the invention consists in certain details of construction and arrangement of parts which will be specifically described in the following specification, reference being had particularly to the accompanying drawings, in which:

Figure 1 is a perspective view illustrating the construction and application of my improved apparatus. Fig. 2 is an enlarged elevation of a union suit forming part of the improvement. Fig. 3 is a similar view showing the suit made up of separable garments. Fig. 4 is an enlarged vertical central section of the mask. Fig. 5 is a similar view showing the opposing half of the mask. Fig. 6 is a fragmentary perspective illustrating the connection of the elastic collar with the mask body. Fig. 7 is a view in front elevation of the improved mask in position. Fig. 8 is a partial side elevation of the mask illustrating the application of the illuminating means above the sight ports. Fig. 9 is a similar view showing the illuminator elevated to permit access to the air valve. Fig. 10 is a longitudinal vertical section through the illuminator. Fig. 11 is a front elevation of the illuminator. Fig. 12 is a broken plan of the inner shell of the illuminator, illustrating particularly the electrical contacts. Fig. 13 is a detail perspective of the switch member for the illuminator. Fig. 14 is a sectional view illustrating the hinge support for the illuminator. Fig. 15 is a vertical sectional view through the ear piece of the mask. Fig. 16 is a perspective of the closure for the mouth opening of the mask. Fig. 17 is an elevation partly in section showing the closure in applied position. Fig. 18 is a transverse sectional view through a modified form of closure for the sight port. Fig. 19 is a front

elevation of one of the sight port closures, showing particularly the movable guard for the transparent material of said closure. Fig. 20 is a similar view illustrating a modified form of guard. Fig. 21 is a fragmentary perspective illustrating the means for supporting and limiting the independent turning movement of one of the sight port closures. Fig. 22 is an elevation of the 10 guard plate and closures for the sight ports, said closures being shown in open position. Fig. 23 is a partial front elevation of an auxiliary mask for use with the suit. Fig. 24 is a sectional view partly in elevation 15 showing a means of communication between wearers of the apparatus. Fig. 25 is a broken sectional view through one of the sight port closures.

Referring particularly to the drawings, 20 wherein is illustrated the preferred embodiment of my invention, the improvement comprises generally a mask 1, designed to protect the head of the wearer and a suit 2 to similarly protect the body and limbs of 25 the wearer. The present invention is more particularly directed to the mask and coacting parts, and while I have illustrated and desire to use one or the other of the forms 30 of suit shown, it is to be understood that the mask may be used alone in those conditions where the wearer is not subjected to extreme heat or cold, or that the mask may be used in conjunction with any desired form of suit.

With particular reference to the mask, as 35 shown in Figs. 4, 5, and 7, it will be noted that the mask comprises a body portion 3 and a crown 4, which parts are adapted for convenient connection or disconnection as will presently appear. The body 3 comprises a metallic casing made up preferably 40 in two or more sections 5 and 6, the terminal edges of which sections are adapted for permanent connection in any desired manner. The body as an entirety is of oval con- 45 figuration in transverse section, with the lower ends or portions of the body section flaring outwardly, as at 7 to fit more or less snugly on the shoulders of the wearer, whereby the weight of the mask and attendant parts is supported from the shoulders. 50 The crown 4 is of approximately semispherical shape in vertical section, being in bottom plan of a size and contour to snugly fit the upper edge of the body. The crown receiving edge of the body is preferably offset or otherwise formed to provide a shoulder 8 and flange 9, adapted to receive and fit complementary parts on the lower portion or edge of the crown, ordinary screws or other 55 fastening means being utilized to secure the crown in applied position.

In the forward or face portion of the body there are formed what I term sight ports 10, which in the preferred form are 60 provided with outwardly extending edge

flanges 11 extending concentric with and bounding the opening. The ports are arranged in position to aline with the eyes of the wearer when the mask is in place, and secured upon the outer surface of the body 70 to surround these ports is a plate 12, preferably an integral structure formed with openings concentric with and in spaced relation to the flanges 11. The plate 12 is adapted to hingedly support the sight port 75 closures, which closures are of identical construction, each comprising an annular band 13 of a size and shape to fit within the edge of the opening in the plate 12 and overlie the flange 11. Each band 13 is provided 80 with a projecting hinge member 14 adapted to be received between ears 15 carried by the plate and mounted on a hinge pin 16 passed through said ears. The relatively 85 forward edge of the band 13 is formed with an integral inturned flange 16, forming a limit for the outward movement of the transparent material of the closure. In this connection it is to be understood that I contemplate the use of any desired material for 90 this purpose, preferring, however, to utilize duplicate sections of isinglass, or other transparent refractory material and a single section of ordinary glass. In securing these sections in applied position I first fix a 95 washer 17 against the inner surface of the flange 16, then apply one of the isinglass sections 18, fitting snugly the inner contour of the band, against the washer. A second washer 19 is then applied against the isinglass section, after which the glass section 20 another washer 21 and the second isinglass section 22 arranged in successive order with a retaining ring 23 frictionally fitting within the band and securing the whole 105 in place.

The relatively inner or proximate surface of each closure is provided with a projecting lip 25, which is adapted when the closures are in applied position to be engaged by a cam locking lever 26 carried by the plate 12 to secure the parts. The lever may be of any desired type, being preferably, however, adjustable to and from the plate 12, through the medium of a screw 110 connection, to provide the desired rigidity of the holding.

Below the sight ports, and in proper relative positions for the wearer I provide the body of the mask with a mouth port 27, the 115 material of the body surrounding the port being preferably projected forwardly to provide a flange 28. A supporting plate 29 is secured to the body encircling the flange of the mouth port and pivotally supports a 120 closure 30 for said port. The particular form of this closure is not of prime essence in the present invention, though I prefer that it be constructed in the form of a cap 125 formed with an annular recess 32 in 130

which is slidably mounted a band 33. The cap ring is provided with radially projecting pins 34 adapted to engage bayonet slots 35 in the flange 28, the cap being interiorly 5 provided with a sealing disk or washer 36 to bear upon the forward edge of the flange and provide an air tight juncture when the cap is in applied position.

The cap is rotatably supported from the 10 hinge connection through the medium of a hinge member 37 supported on a pivot pin removably mounted in ears 38 formed on the plate 29, said hinge member having spaced arms 39 to encircle the cap and engage the 15 band 33. A peculiar connection is made between the arms 39 and band 33 which is illustrated more particularly in Fig. 21. This connection is provided by forming an offset or thickened portion 40 in the band at 20 the proper point, which portion is formed with a longitudinally extending slot 42, said slot being formed at one end with a lateral enlargement or extension 43. The terminals of the arms 39 are provided with two pins 25 44 and 45, one of which is designed to rest in the slot 42 and the other in the enlargement 43 thereof. By this construction sufficient movement is permitted the cap or closure in removing or applying the same, while 30 the pin 45 serves to limit any independent swinging movement of the cap which might tend to so displace it as to render considerable time necessary in arranging it in applying position.

35 In the side portions of the body and in proper relative position I form what I term ear ports 46, and in conjunction therewith make use of closures therefor as illustrated in Fig. 15. These closures comprise hollow 40 metallic sections 47 formed near their inner edges with radially projecting flange 48. The material of the ear closure beyond the flange 48 is perforated as desired, and within the section is secured a disk 49 of sound 45 transmitting refractory material, said disk preferably resting against a shoulder formed within the section and secured in place by a friction band 50. The ear closure is applied by inserting the inwardly projecting portion of the section within the opening, the flange 48 overlying and resting against the body and being removably secured thereto in any preferred manner. Arranged below the eye port and to one side of the mouth 50 port are valve sections 51 and 52, said valves being preferably of duplicate construction and secured in any preferred manner in openings formed in the body. As more 55 clearly seen in Fig. 24 the valves are arranged for automatic closing against outlet from the interior of the body, being preferably provided with conical valve points spring pressed outwardly against appropriately formed seats. As shown in Fig. 7 the 60 valves are each exteriorly threaded for con-

nection with auxiliary parts to be later described. The body is also formed with an opening 54 in which is secured an audible signal or alarm. This signal is preferably in the form of a whistle and comprises a bracket 55 secured to the outer surface of the body and carrying a depending stem 56 in open communication with the interior of the body through the opening 54. Spring held within the stem 56 is a whistle member 57, adapted in normal position to be secured within the stem in a manner to form an air tight connection. The whistle is manually movable, however, to arrange the whistle opening therein below the lower end of the stem 56, so that the operator by drawing downward on the whistle 57 to expose the whistle port and blowing through a flexible tube 58 projecting within the body, may sound the whistle, or other preferred form of alarm, to signal as desired.

The crown 4 is utilized as the main air reservoir for the mask, being for this purpose formed or provided with an inner shell 59 spaced from the upper wall 60 of the crown. The shell is curved on a somewhat greater radius than the curvature of the crown wall, thereby providing in effect an air chamber 61 between the shell and wall which is approximately of crescent shape in 90 transverse section. By this means the maximum storage space is provided and the full rigidity of the walls secured through their curved formation is assured, though it is to be understood that if desired reinforcing 100 posts 62 may be used to brace the walls of the air chamber. In the relatively forward portion the air chamber communicates with a depending port 63 controlled by a valve 64, the stem of which opens through 105 and is operable beyond the exterior wall of the crown. The port 63 communicates with a flexible tube 65 which depends within the body of the mask to a position adjacent the mouth port, thus enabling the wearer, by a 110 proper operation of valve 64 to maintain a desired supply of air from the reservoir.

In connection with the main reservoir 61 I provide the mask with an auxiliary reservoir 66, preferably removably secured to the 115 rear portion of the body of the mask. The tank or reservoir may be of any desired size or configuration, being formed with a valve outlet 67, which communicates through a pipe extension 68 with a valve inlet 69 120 of the main reservoir 61. The outlet 67 is controlled by a valve 70 which preferably extends throughout the length of the tank and is operated through the medium of a milled head 71 arranged below the tank. 125 It is of course to be understood that the auxiliary reservoir 66 is provided with a gage 71 to indicate the pressure of air within the reservoir and also that if desired the pipe connection 68 may be disconnected 130

from the main reservoir to permit the independent filling of said main reservoir from any suitable source. The auxiliary reservoir 66 is provided with a charging valve 72 of any desired or preferred construction, such for example as the usual tire valve.

The auxiliary reservoir is designed to act, when in use, as a storage chamber for the main reservoir, it being noted in this connection that the valve 69 opens automatically inward, so that with the valve 70 opened the pressure in the main and auxiliary chambers will balance and the air supply in the auxiliary tank will continually recharge the main tank as the air is drawn from the latter. The auxiliary tank has another and important function which will later appear.

In order to accommodate the apparatus for continued as well as emergency uses I contemplate the use of an additional air supply, which may be delivered directly to the wearer independently of the main and auxiliary reservoirs. For this purpose, as will be evident from Fig. 1 I provide an additional tank 73, which is adapted, through the medium of a handle 74, for being carried in the hands of the wearer or for being removably suspended from a hook or strap forming part of the suit. The tank 73 is provided with a charging valve 75 and with a supply tube 76 leading from the tank and adapted for removable engagement with the valve 51 of the mask. Within the mask a mouth tube 77 leads from the valve 51 to a point adjacent the mouth port, and the supply tube 76 is provided at a convenient point in its length with a manually operable valve 78, upon proper operation of which the wearer may gain his air supply directly from the tank 73 without utilizing the air in the main or auxiliary tanks, the valve 64 in this use being of course closed.

In conjunction with the mask described I make use of an illuminating means removably connected with the mask and directly controlled by the wearer. Such illuminator is more particularly illustrated in Figs. 10, 11, 12 and 13, wherein it is seen to comprise an inner shell 79, provided with one or more incandescent lamps 80 and rearwardly beyond the lamp with a suitable reflector 81 of any desired type. The lamp energizing means preferably comprises batteries 82 fixed in housings on opposing sides of the shell 79, said batteries being in circuit with the lamps and each having conductors 83-84 which on the lower side of the shell terminate in spaced contacts 85-86. The respective contacts 86 of the batteries are arranged in the same plane with their free ends slightly divergent, and a switch member 87 is mounted on the shell comprising a rod 88 mounted in bearing brackets and carrying an insulated plug 89

adapted on rotation of the rod to be forced between the contacts 86 and spread them into engagement or contact with the members 85, thereby closing the circuit and lighting the lamps. The rod 88 is provided with a handle member 90 disposed within convenient reach of the operator so that the lights may be switched on and off at will. In connection with the inner shell 79 the illuminator comprises an outer shell 91 in which the inner shell is adapted to be inserted and held against longitudinal movement by a rim 92 removably engaging the forward edge of the outer shell and having an inwardly extending flange 93 to overlie the forward edge of the inner shell, screws or other fastening members passing through the flange 93 and engaging threaded abutments in the interior of the outer shell securing the parts in applied position. The rim 92 is provided with a guard 94, preferably of connected wire lengths, as shown in Fig. 11, said guard being hinged to the rim at 95 and secured in closed position by a hook 96. A lens 97 is secured within the inner shell at an appropriate point within the length of the latter, and between the forward wall of the inner shell and the flange 93 of the rim is arranged a disk of isinglass or the like 98, the edges of which are secured to the flange 99 of the shell 79, which, when the parts are in applied position, form an air tight connection between the shells.

The illuminator is adapted for connection with the mask in one or two places, either above the sight ports on the crown of the mask, or below said ports encircling the mouth port. The wearer may thus have the illuminating beam above or below his sight as the requirements of the particular situation may demand. For the purposes of the lower connection the outer shell of the illuminator is provided at one point with a hinge member adapted to be received between ears 100 formed on the body of the mask, and at a diametrically opposite point with outwardly projecting curved lips 101 arranged in spaced relation to receive between them the stem of a cam lever 102. The cam portion of this lever engages the curved surfaces of the lips and firmly secures the parts in applied position.

For supporting the illuminator in the upper position I provide the outer shell with a hinge member 103 adapted to be received between ears 104 formed on the crown and engaged by duplicate pivot pins 105 mounted respectively in the ears and reciprocating in alignment transverse the ears to meet end to end in operative position, the pins being withdrawn through the medium of finger plates 106 terminally connected to the pins and pivotally supported intermediate their ends in slots formed in the ears. The free or operative ends of the plates extend be-

yond the outer surfaces of the ears and are spring pressed in an upward direction, permitting the pins to be normally in contact and separated at will through the operation 5 of the plates. In the upper position the lower portion of the illuminator is secured against movement by offsets 107 formed on the outer shell engaging spring catches 108 removably or otherwise secured to the 10 crown.

The body of the mask is formed with an exhalation opening 109, in which is fitted a valve 110 so constructed as to permit the convenient escape of the exhalations of the 15 wearer. The valve 110 may be either of the automatic type arranged to permit free egress and prevent ingress, or may be of the manually adjustable type by which the escape of the fluid may be regulated as desired. In connection with the main reservoir in the crown it is important that means be provided for indicating at all times the pressure within said reservoir, and it is also of importance that the indicating means be 20 readily visible from both inside and outside the mask. For this purpose I provide the body of the mask with a gage opening 111, which opening has a surrounding edge flange 112. A double face gage 113 is in 25 communication with the main reservoir through a pipe 114, said pipe adjacent its connection with the gage being laterally projected to offset the gage proper and permit it to be positioned within the flange 112. 30 A cap 115 formed with an inspection opening covered with isinglass or similar material is adapted to be screwed or otherwise secured in an air tight manner on the flange 112, the inspection opening being arranged 35 to permit reading of one face of the gage. The opposite face of the gage is, of course, entirely visible to the wearer of the mask, and, therefore, he may readily advise himself at any and all times of the pressure, 40 and, therefore, the supply of air at his command.

The body and cap of the mask are preferably both lined and covered with a layer of asbestos, as in the form of a sheet, the 50 asbestos layers 115 forming the covering and lining to the crown, being secured in place in any desired manner, as by gluing or the like. The covering and lining 116 of the body are similarly secured in place, 55 the various supporting plates, valve connections and other parts described as secured to the body overlying the covering therefor and additionally securing said covering in place. The front and rear portions of the 60 body covering extend below the lower edge of the body in the form of aprons 117, which, when the mask is in place, are adapted to overlie the forward and rear portions of the body of the wearer, as shown in Fig. 1, 65 the side edges of the aprons being respec-

tively provided with hooks and adjustable buckles, whereby said aprons may be tightened in position to firmly and properly secure the mask on the shoulders of the wearer. The auxiliary reservoir 66 is also preferably covered with a layer of asbestos 70 118, which either integrally or sectionally is projected below the reservoir in the form of a pocket 119, which has a side opening. The pocket 119 is adapted to contain a flexible 75 mask 120, such for example as shown in Fig. 23, said mask being in valved communication with the auxiliary reservoir 66 through a flexible pipe 121. The forward apron is also provided with a pocket 122, adapted to contain auxiliary parts which may be of assistance to the wearer, such for example as an asbestos sheet which may be utilized in enveloping a victim in carrying him through flame exposed situations. The 80 pocket closures are preferably secured in position through use of the ordinary glove fasteners or the like, and I also contemplate the use of said fastenings to maintain the asbestos sheet in flat condition within the 85 pocket as desirable, said sheet being folded so that it may be properly supported from two corners which are provided with female portions of the fasteners and are adapted to engage the male portions fixed within the 90 pocket. 95

The additional tank 73, which may or may not be asbestos covered, is also provided with a pocket 123 in which is placed an additional flexible mask, having an inlet 100 valve arranged for the connection of the flexible tube 76. By this construction the wearer of the suit may in the event of finding a victim, who cannot be removed at once, detach the pipe 76 from connection with his mask, connect the same with the auxiliary mask carried in his pocket 123, and apply the mask to envelop the head of the victim, thus providing the victim with a supply of fresh air until such time as he can be removed. The tank 73 is also preferably provided with a pressure gage 124 inset to avoid projection beyond the surface of the tank, and serving to all times indicate the pressure in the tank. 110

In connection with the mask I contemplate the use in those situations when necessary of a protective uniform further covering the body and limbs of the wearer. This uniform 2, as shown in Fig. 2, may be of the ordinary union type, the material of course being of some fire resisting material. As shown in Fig. 3 the uniform is of the separate garment type, which in some instances may be found desirable. The various connections for the garment are preferably quick adjusting buckles and hooks, so that the garment may be quickly applied or removed. The union garment is particularly 120 desirable for individual use in emergency 125 130

cases, as it may be quickly applied and is ordinarily of lighter construction than the independent garment uniform.

If desired the crown of the helmet may be provided with radially disposed stiffening ribs 125, serving to prevent crushing of the crown under the impact of a falling object. The invention further contemplates the use of a shield 126 which may be removably connected in the hinge fastening for the upper illuminator when the same is not in use, said shield comprising an appropriately shaped plate 127 designed to project from the crown a sufficient distance to deflect falling objects from the eye closures or other projecting parts of the mask.

With the mask I use an elastic air excluding collar 128, preferably in the form of a circular section of rubber material. This collar is centrally formed with an opening adapted to be passed over the head of the wearer and snugly embrace the neck without of course undue pressure. The edges of the collar are removably secured to the body of the mask in any desired manner, preferably, however, seating in an annular channel 129 formed in the body and secured by an overlying split ring 130 adapted to snugly fit in the channel, the proximate ends of the ring being formed with semicylindrical notches 131 adapted when in place to embrace a pin 132 projecting from the base of the channel. If desired the pin 132 may be in the form of a headed screw to be passed through the registering notches 131 and threaded into an opening formed in the base of the channel, the collar, of course being formed with an opening 133 to permit such connection. In Figs. 18 and 22 I have illustrated a modified form of closure for the sight port, in which the supporting plate 134 for said closure is practically identical with that in the preferred form. In this form the closure is in the form of an annular band 135 supported on hinged arms 136 mounted and operated as described in connection with the mouth closure, the connection of said band with the projections from the body being of the bayonet slot type as previously described.

If desired the bayonet slot connection may be dispensed with and the ordinary screw thread 137 formed on the band and on the projection from the body to provide the desired connection. The bands are provided with the protective transparent material assembled in the manner previously described in connection with the preferred form, though in this instance said material bears against an annular flange 138 formed interiorly of the band. Overlying the flange is what I term a combined guard and cleaner, comprising an open work wire frame 139, which may be of the form shown

in Figs. 19 or 20, and which is provided with laterally projecting feet 140, secured to an annular band 141 designed to fit within the band 135. Overlying the band of the guard is a retaining ring 142 adapted to exert the desired pressure upon the outer washer of the transparent material. The band 141 of the guard lies within the vertical depending wall of the retaining ring, so that said guard is freely rotatable within the band 135. The guard thus effectively protects the transparent material and at the same time may be freely revolved to assist in cleaning said material.

In Fig. 24 is shown a means for communication between two wearers of the apparatus, such comprising a flexible tube 143, of any desired length, said tube carrying at one end a valve casing 144 in which is arranged a normally spring closed valve 145, the stem 146 of the valve projecting into approximate alinement with the free edge of the casing. The opposite end of the tube is also provided with a valve casing 147, connected to the portion of the body 3, said casing 147 having an outwardly pressed stem 149. The valve casing 147 is threaded for connection with the valve section 52 of the body, the parts being so arranged that when said valve section is in position the pressure of the respective stems 149 and 53, through mutual contact will normally set the valves open. The valve casing 144 is designed to be manually applied to the ear piece of the other mask, said casing resting against the convex wall of the ear piece causing the higher portion of said wall to fit within the casing and by pressure on the end of the stem 146 to open the valve. As long as the valve casing 144 is held in position on the ear piece an uninterrupted communicating tube is provided between the mask, through which desired communication may be held, the opening of valve section 52 within the mask being preferably provided with a flexible mouth piece 150 for the more convenient use of the wearer.

As will be particularly noted in Fig. 7 I contemplate if desirable to provide the preferred form of eye closure with the guard members 94 described in connection with the illuminators, such illustration being intended to indicate any preferred or desired form of protective guard for the eye closure.

The application and use of the improved apparatus will be plainly apparent from the above description taken in connection with the drawing, it being understood that with the mask applied and not immediately desired for use the wearer may secure the desired quantity of fresh air by opening one or the other of the eye closures; that when in use and in traveling considerable distances to the point of service the wearer may utilize the air drawn from the addi-

tional tank 73 without drawing upon his supply in the main or auxiliary reservoirs; that having reached the point of immediate use the additional tank may be discarded 5 entirely or left for the benefit of a victim impossible to at once remove; that the wearer may, if conditions warrant the same draw upon the air in the main reservoir and automatically supplement the pressure 10 therein from the auxiliary reservoir; that on finding a victim desired to be removed, the wearer may utilize the auxiliary mask 120 and supply air thereto from the auxiliary reservoir 66, of course, in this instance cutting off communication between the auxiliary and main reservoirs; that in removing the victim through flame exposed situations the asbestos sheet from the pocket 122 may be removed and wrapped about the 15 victim to protect his body from the flames; that the wearer may indicate his presence to others, or signal orders through the whistle alarm described; and that a number of individuals each wearing one of the masks 20 may readily communicate with each other 25 in the manner described.

The apparatus is designed to be constructed as light as consistent with the desired strength, and for this purpose the 30 use of any appropriate material of any metallic character is contemplated. Furthermore, the exact form of the various parts is not absolutely essential and I contemplate varying such form in any manner desirable 35 by the particular conditions.

Hand coverings are also removably secured to the mask aprons by glove attachments, rendering them readily accessible for use if desired. These coverings are preferably of the mitten form, as shown at 152 in Fig. 1. The inner surfaces of the aprons, 40 at respectively contacting points are also

provided with glove fastenings 153, whereby said aprons may be turned upward and secured in that position when the mask is 45 not in use, thereby avoiding interference from the aprons in applying the mask.

Having thus described the invention what is claimed as new, is:—

1. A protective uniform including a 50 mask comprising a body and a detachable crown, said crown being provided with an air reservoir, and means for reinforcing said crown and the walls of said reservoir.

2. A protective mask, a reservoir carried 55 thereby and in communication therewith, said reservoir being provided with a pocket, and an additional mask carried in said pocket, said latter mask being in valve communication with the reservoir.

3. A protective mask having an air reservoir, and a pressure gage in communication with said reservoir, said gage being readable from both the inner and outer sides of the mask.

4. A protective mask formed with an air reservoir, and a pressure gage in communication with the reservoir, said mask being provided with an opening in the side thereof, said gage being readable from both the 70 inner and outer sides of the mask.

5. A protective mask, an illuminator therefor, and means for removably connecting the illuminator to the mask, said means being arranged to permit a swinging of the 75 illuminator with relation to the mask without disconnecting the illuminator from the mask.

In testimony whereof I affix my signature in presence of two witnesses.

WILLIAM JOSEPH MORAN.

Witnesses:

JOHN L. FLETCHER,
D. W. GOULD.
